UNITED STATES PATENT OFFICE.

WILLIAM H. PERRY, OF CONCORD, NEW HAMPSHIRE.

DESIGN FOR A MONUMENT.

SPECIFICATION forming part of Design No. 21,536, dated May 10, 1892.

Application filed April 18, 1892. Serial No. 429,677. Term of patent 3½ years.

To all whom it may concern:

Be it known that I, WILLIAM H. PERRY, a citizen of the United States, residing at Concord, in the county of Merrimac and State of New Hampshire, have invented and produced a certain new and original Design for Monuments, of which the following is a specification.

In the accompanying drawing I show reference letters and figures denoting the various features of my design. An oblong base 1 has four vertical sides terminating at their tops in an obtuse frustum of a pyramid 2. An oblong pedestal 3 rests upon said frustum 2 and has four vertical sides terminating at their tops in an acute frustum of a pyramid, as seen at 4, one or more sides of which have thereon a raised tablet 5. The shaft is also oblong, having four vertical sides 6, which terminate in a cornice 7, which consists of a concave curve 7', extending outward from said shaft to the vertical sides 8, from the extreme upper edge of which the top rises in the form of a four-sided wedge 9. One or more of the ver-

tical sides 8 of said cornice may have an upward extension 10, the sides of which meet at the point 11 and extend inward to the said wedge-shaped top 9.

Other features of my design are the tablets 12, formed upon said wedge-shaped top 9, having the configuration shown, the tablets 13, formed upon the said shaft 6, being simply rectangular in outline, and the manner of finishing the various parts represented by reference-letters A B C in the drawing—to wit, 35 A indicating rock-work, B hammered work, and C polished work.

Having described my invention, what I claim is—

The design for a monument, substantially as herein described and shown.

In testimony whereof I affix my signature in presence of two witnesses.

WILLIAM H. PERRY.
